UNITED STATES PATENT OFFICE.

FRANK BLOISE AND FRANK REDA, OF BROOKLYN, NEW YORK.

COLLAR, LAPEL, AND FACING CONSTRUCTION FOR COATS AND SIMILAR GARMENTS.

Application filed September 8, 1924. Serial No. 736,496.

This invention relates to coats, jackets and similar garments and particularly to the formation of the collar, lapel and facing portion of such garments and still more particularly to the construction of collar, lapels and facings of unitary or one-piece construction in striped goods or fabrics whereby the stripes of the goods will be continuous in one direction throughout the collar, lapels and facings; and the object of the invention is to provide a construction of the class specified in which a single pattern piece is provided for constructing a unitary collar, lapel and facing part or member for a garment; a still further object being to provide a pattern piece which is so laid out and formed as to permit of the cutting of a piece of goods from which the unitary structure is to be formed with the stripes of the goods extending uniformly through the collar, lapel and facing construction; and with these and other objects in view, the invention consists in a garment part of the class specified constructed in the manner and in accordance with the method hereinafter described and claimed.

The invention is fully disclosed in the following specification, of which the accompanying drawing forms a part, in which the separate parts of our improvement are designated by suitable reference characters in each of the views, and in which:

Fig. 1 is a perspective view of a jacket, the collar, lapel and facing portion of which is made according to our invention.

Fig. 2 is a diagrammatic view of a piece of goods with a pattern piece mounted thereon indicating the method of placing said pattern and cutting the goods to form our improved garment part.

Fig. 3 is a perspective view of the method of laying out the pattern piece.

Fig. 4 is a detail view of the garment piece made according to our invention and illustrating the method of fashioning the collar portion thereof; and,

Fig. 5 is a detail view of the garment part cut from the fabric by the use of the pattern as shown in Fig. 2 of the drawing.

Heretofore it has been customary in the formation of the collar, lapel and facing portion of a coat or jacket, to fashion the collar proper independent of the facing and lapel portions of the garment and to attach the collar to the lapel portions at the notches usually formed therein, and with the present

method of procedure, it has been found to be practically impossible to properly match the stripings in a striped fabric so as to extend from the lapel portions of the garment through the collar portion thereof, and if this result is accomplished, considerable pains must be devoted to the construction of the collar and lapel portions of the garment. The distinctive feature of our invention is to so cut the unitary collar, lapel and facing garment part from a piece of fabric, and to provide a properly constructed pattern piece for the accomplishment of this result, whereby the stripes of the fabric will extend evenly and continuously through the facing, lapel and collar of the garment to produce a neat and finished appearance.

In carrying our invention into effect, we first construct a pattern piece 10 shown in Fig. 2 of the drawing and indicated in dotted lines in Fig. 3 of the drawing, in which latter figure, the method of laying out the pattern piece is diagrammatically illustrated, and in the use of the pattern piece, the collar forming portion 11 thereof is placed with its end adjacent the folded edge 12 of a sheet of striped fabric 13, the strips of which extend longitudinally of the sheet and parallel with the fold 12 thereof. The pattern piece 10 is also placed in such manner that the outer edge of the lapel forming part 14 extends in parallel relation with the stripes of the fabric, except for any curvatures or roundings that may be desirable in the formation of the lapel or the facing of the coat or jacket as shown at 15 in Fig. 2 of the drawing.

When the fabric 13 is cut out from the pattern 10 shown in Fig. 2 and the fabric extended, the substantial result of this operation is indicated in Fig. 5 of the drawing, in which it will be noted that the stripes 13^a of the fabric 13 in the garment part 16, formed as above set out, extend continuously through the facing, lapel and collar portions of said garment part, and the stripes are in substantially parallel relation with the straight or outer edge 17 of the lapel portions of said garment part as clearly illustrated in Fig. 1 of the drawing.

In securing the garment part 16 to a coat, jacket or other garment in accordance with the usual methods of constructing garments, it will be understood that the garment part 17 is folded on the dotted line 18 indicated in Figs. 4 and 5 of the drawing and also

- represented on the pattern piece 10. Prior to securing the garment part 16 to the remainder of a garment, it is preferred that the inner or facing portion of the collar of said garment part, be stretched laterally from the central portion thereof as indicated at 19 in Fig. 4 of the drawing, this operation effecting a proper fitting of the collar around the neck of a wearer.
- 10 It will be noted on a consideration of Figs. 2 and 3 of the drawing, that the pattern piece when folded, or a one-half pattern piece, or a garment part cut therefrom, is of such construction that the outer edge of the 15 lapel and part of the facing forming portion of the pattern of such garment part is parallel with the straight edge of the half or folded pattern piece from which the central portion of the collar is formed or in 20 other words is parallel with the folded edge of the garment part cut from said pattern piece in the manner illustrated in Fig. 2 whereby the resulting product or garment part will have arranged thereon, the 25 stripes of the fabric in parallel relation to the outer edge of the lapel and facing portions thereof, and also parallel to the folded edge of the fabric, see Fig. 2, from which the garment part is formed.
- 30 It will be understood that the pattern piece 10 must be properly laid out to suit a predetermined garment size to effect a proper fitting of the garment, and especially the 35 part 16 of the garment, constituting the unitary collar, lapel and facing construction. It will be noted that the facing and lapel portion proper extends at right angles to a tangent line extending from the curvature of the collar, or in other words, the collar is 40 curved and extends in a direction at right angles to the longitudinal line of the facing and lapel, as viewing the pattern piece from which one half of the complete garment part is formed. It has been found that in practice a garment constructed with my improved unitary garment part, will provide a 45 perfect fitting around the neck and shoulders of a wearer, if the size of the garment is correct for such wearer, and the completed 50 product produces a far better and neater appearance in the entire garment, and it will also be understood that a material saving in time and labor, especially in the skill of a cutter and fitter, is eliminated or obviated 55 in that the unitary garment part constructed and fashioned in the manner set out is bound to properly fit a given size when such garment part is cut to the said given size. It

will also be understood that the complete garment part may be cut from an extended 60 piece of fabric by using an extended pattern piece or part in accordance with the present procedure of tailoring, in which operation, the separate side portions of the pattern piece will lie in the same manner as the half 65 pattern piece shown in Fig. 2 of the drawing, and other changes in and modifications of the construction and method of procedure herein set out, may be made within the scope 70 of the appended claims without departing from the spirit of our invention or sacrificing its advantages.

Having fully described our invention, what we claim as new and desire to secure by Letters Patent, is:—

75 1. A pattern piece for forming a unitary collar, lapel and facing garment part from predetermined fabrics, the outer edge of the lapel forming portion of said pattern piece being parallel to a line extending vertically 80 through the central part of the collar forming portion of said pattern piece.

2. A garment part of the class described, the collar, lapel and facing portions of which are of unitary construction and so 85 fashioned from a predetermined striped fabric as to provide continuous arrangement of the stripes of the fabric entirely through the collar, lapels and facings, in lines parallel to the outer edges of said lapels. 90

3. The herein described method of forming a garment part of unitary construction comprising collar, lapels and facings, which consists in providing a pattern piece, the outer edge of the lapel forming portion of 95 which is parallel to a vertical line extending through the central portion of the collar forming portion thereof, placing said pattern piece on a striped fabric with the outer edge of the lapel forming portion of 100 the pattern in parallel relation with the stripes of the fabric and cutting the garment part from the fabric along the lines of said pattern piece whereby in the resulting product, the stripes of the fabric extend through 105 the collar, lapels and facings in parallel relation to the outer edges of the lapels, folding said garment part to form the collar, lapels and facings, and fashioning the inner or facing portions of the collar to properly 110 fit around the neck of a wearer.

In testimony that we claim the foregoing as our invention we have signed our names this 5th day of Sept., 1924.

FRANK BLOISE.
FRANK REDA.
